UNITED STATES PATENT OFFICE

2,474,984

FRAME INVERTER

William F. Pioch, Detroit, Mich., assignor to Ford Motor Company, Dearborn, Mich., a corporation of Delaware

Application February 8, 1947, Serial No. 727,441

4 Claims. (Cl. 214—1)

1

This application is concerned with a materials handling system and more particularly with a system for conveying and manipulating vehicular chassis during manufacturing operations.

The use of a constantly moving conveyor system or "assembly line" is almost universal practice in the automotive industry. The initial unit to be placed on the assembly conveyor is usually a prefabricated frame. As a matter of convenience this frame is first mounted on the conveyor horizontally, but inverted from the position it will assume in the completed vehicle. This permits the addition of those parts which are secured to the underside of the frame without the difficulties inherent in working on the underside of the assembly. As an example, the rear axle assembly on certain vehicles is so designed that it is installed more readily when the frame is inverted.

When all the desired components have been added to the underside of the frame, the assembly is rotated 90 degrees about its longitudinal axis into a vertical position. While in this position, it is carried through a spray booth where a final protective coat of paint is applied. After the painting operation has been completed, the assembly must be rotated through another 90 degrees into a horizontal position. Each of the above-mentioned rotations are in the same direction, so that the result is that the chassis are moved from an inverted position to the normal position and are ready to receive further components which are best added from the top of the chassis.

Accordingly, it is an object of this invention to provide an apparatus for conveying and inverting vehicular frames during assembly.

It is a further object of this invention to provide an apparatus whereby a vehicular frame may be inverted completely, or held at any intermediate position between the normal and inverted positions.

With these and other objects in view, the invention comprises the arrangements, constructions, and combinations of the various elements of the structure described in the specification, claimed in the claims and illustrated in the accompanying drawings, in which:

Figure 1 is an elevation of that portion of the inverted mechanism and which is supported upon the overhead monorail of the conveyor system.

Figure 2 is an elevation of the inverter assembly showing a frame in place and in the inverted position.

Figure 3 is an elevation of the inverter assembly showing a frame in place, with an axle assembly

added and rotated into the proper position for painting.

Figure 4 is an elevation of the inverter assembly showing a frame in place and rotated into the position it occupies in the completed vehicle.

Figure 5 is an elevation of the channel cams showing the positioning upon the monorail of the channel cam elements employed to rotate the frame and return the sling to the starting position.

Turning to Figure 1, the monorail upon which the assemblies are supported is indicated by 10. Yoke 11 is supported on monorail 10 through rollers 12. Spider 13 is rotatably supported at the bottom of yoke 11 in bushing 14. Spider 13 is provided with a plurality of radial appendages 15 terminating at their outer ends in rollers 16. The purpose of appendages 15 and rollers 16 will become apparent as the description proceeds. In the instant case there are nine appendages and rollers with #1 roller 16 on #1 appendage 15 shown in engagement with #1 channel cam 17 which is rigidly secured to the underside of monorail 10.

25 In Figures 2, 3 and 4, the relationship between the structure of Figure 1 and the remainder of the assembly is shown. Here a frame 18 with superimposed axle assembly 19 is shown supported by sling 20 and bracket 21 secured thereto.

30 It is to be noted that spider 13 occupies the same position in Figures 1 and 2 and that #1 appendage is upright and in engagement with #1 channel cam 11. This represents the instant just prior

35 Prior to this time, all work on the underside of the frame has been completed.

Sling 26 may be fabricated from rope, cable, chain or any strong and flexible medium. How-

chain or any strong and flexible medium. However, it is preferred to make at least a portion of the sling 20 of chain since a positive engagement of the sling 20 with the spider 13 is required. A portion of the spider 13, not shown, carries sling 20 and is provided with teeth for engaging positively the chain of sling 20. Thus, any rotation of spider 13 in bushing 14 must result in a corresponding movement of sling 20. To provide positive engagement of sling 20 and frame 18, bracket 21 is provided.

Figure 5 is a plan view of monorail 10 with a series of channel cams 17 mounted on its underside. In Figures 1 and 2, #1 roller 16 is engaging the #1 channel cam 17.

As the entire assembly moves along monorail 10 clockwise from point A, the cam action of #1 channel cam 17 on #1 roller 16 causes a counter-

clockwise rotation of spider 13 as viewed in Figure 2. Before #1 roller 12 becomes free of #1 channel cam 17, #2 roller 16 has engaged #2 channel cam 17 and so the rotation of spider 13 is continued. Since a positive engagement of sling 20 and spider 13 is provided, this rotation of spider 13 causes a rotation of bracket 21 and frame 18 roughly about the longitudinal axis of the frame. Successive rollers 16 continue to engage successive and like numbered channel cams 17 in regular order until #7 roller 16 moved by #7 channel cam 17 is on the upper center line. At this point the frame has been rotated to an approximately vertical position for the painting operation. This is the position depicted in Figure 3. Also at this point, indicated at B in Figure 5, the normal slope of #7 channel cam 17 changes and parallels the center of monorail 10 for a distance determined by the distance required for the completion of the painting operation. Thus further rotation of spider 13 and the frame 18 is prevented during the painting. At a point C on the line marking the conclusion of the painting operation #7, channel cam 17 again departs from the center line of the monorail and rotation of the spider 13 and frame 18 continues. This process repeats for a total of 12 channel cams 17 or until spider 13 has made approximately one-and-one-third revolutions. This places the frame in the right-side-up position shown in Figure 4. When the center line of the twelfth channel cam 17 intersects the center line of monorail 10 at D, this channel cam 17 begins to parallel the monorail 10. This holds the frame in a right-side-up position until all required work is completed and the frame is transferred to a separate moving conveyor belt and the weight removed from suspension 20.

The monorail 10 is, of course, arranged to form a closed circuit as shown in Figure 5. After the suspension 20 has been freed of the assembly, the center line of the #3 channel cam 17 departs from the center line of monorail 10 at E in such a way as to reverse the previous direction of rotation. Through a similar series of channel cams, the spider 13 is reversed to its original position. The last channel cam of this reverse series must, of course, merge with #1 channel cam 17 as illustrated in Figure 5. Thus, an automatic return to the original position ready for the reception of another frame is provided.

I claim as my invention:

1. In a materials handling system, an overhead track arranged in closed circuit, a yoke arranged to move along said track, a spider member rotat-

ably supported in said yoke, a sprocket arranged to rotate with said spider member, a sling, a portion of which is in positive engagement with said sprocket, a series of radial arms secured to the spider and fixed cam surfaces adapted to engage said radial arms and impart a rotary movement to the spider.

2. In a materials handling system, an overhead track arranged in a closed circuit, a yoke arranged to move along said track, a spider member rotatably supported in said yoke, a sprocket arranged to rotate with said spider member, a sling, a portion of which is in positive engagement with said sprocket, a bracket secured to said sling at a position remote from the sprocket, a series of radial arms secured to the spider and fixed cam surfaces adapted to engage said radial arms and impart a rotary movement to the spider.

3. A positioning device for incomplete assemblies comprising an overhead track arranged in a closed circuit, a series of cam surfaces on the underside of the track, a yoke arranged to move along said track, a spider member rotatably supported in said yoke, a sprocket arranged to rotate with said spider member, a sling, a portion of which is in positive engagement with said sprocket, a series of radial arms secured to the spider, said cams, spider and sling being arranged to hold the assembly in one position for the duration of the first operation, to rotate the assembly to a second position for a second operation and hold this second position for the duration of the second operation, and then to further rotate the assembly into a third position and secure the assembly in this position for the duration of a third operation.

4. The device recited in claim 3 in which a second series of cam surfaces is provided in the return circuit and after the termination of the final operation, which rotates the spider in a direction opposite to and an amount equal to the original rotation.
